UNITED STATES PATENT OFFICE.

ALMA H. ANDERSON, OF INDIANAPOLIS, INDIANA, ASSIGNOR TO THE SPECIALTY MANUFACTURING COMPANY, OF SAME PLACE.

DESIGN FOR A HANDLE FOR POSTAL MARKING AND CANCELING STAMPS.

SPECIFICATION forming part of Design No. 28,645, dated May 17, 1898.

Application filed December 3, 1897. Serial No. 660,708. Term of patent 7 years.

To all whom it may concern:

Be it known that I, ALMA H. ANDERSON, a citizen of the United States, residing at Indianapolis, in the county of Marion and State 5 of Indiana, have invented a certain new and useful Design for a Handle for Postal Marking and Canceling Stamps, of which the following is a specification.

Figure 1 is a view in perspective of a handle, showing my new design; and Fig. 2 is a plan view of same.

Referring to the drawings, the leading or material feature of my design consists of the rounded portion A, having a ferrule *a*, and a 15 thin flat blade-like extension B, projecting from the ferruled end of the handle. The part B tapers slightly toward its outer end and terminates with the head C, which stands in a plane parallel with the handle, but be-

low it, because of the downward bend D from 20 the body of the part B and the forward bend E. The peculiar shape of the part B, resulting from the bends D and E, constitutes the important and essential feature of my design.

Having described my invention, what I 25 claim as new, and desire to secure by Letters Patent, is—

The design for the handle of a postal marking and canceling stamp, as herein shown and described.

In witness whereof I have hereunto set my hand and seal, at Indianapolis, Indiana, this 29th day of November, A. D. 1897.

ALMA H. ANDERSON. [L. S.]
